PERIODICAL HOLDER

Alfred George Scholz, San Francisco, Calif.

Application August 2, 1940, Serial No. 349,452

5 Claims. (Cl. 129—39)

This invention relates to a holder for periodicals and more particularly to such a device wherein only slight additional weight is added to the original magazine or periodical so that a user does not tire from holding the same. The device is one wherein the conveniences added by use thereof far offset any of the possible disadvantages.

It is known in the art to have periodical holders or covers in which a single periodical or successive numbers or issues are added therein to form a substantial binder. The most usual way of maintaining the magazine within a binder of this nature is to have some device such as a bar, a strip or a rod which is adapted to fit down through the individual periodical approximately at the center leaf where the binding staples are usually placed and which is attached firmly in some manner, to both top and bottom of the cover at the inner side of the back. Whether these covers be flexible or stiff, in order to be at all serviceable and still present a pleasing appearance, they must be made of such material and constructed in such a manner as to withstand continued and frequent use. Of necessity they are heavy and very inconvenient to hold. It is an object of the present invention to provide a holder which will supply the needs for various sizes of magazines and which will be readily adapted to use with one periodical, providing comfort of handling without the added weight. The present invention is not to be confused with any kind of permanent binder but is simply a convenience in connection with the enjoyment of the usual magazine or periodical.

It is an object of the present invention to provide a supporting means for a periodical which combines the objectives herein disclosed or which are inherent in the device.

A large number of the binders or backings or other supports for periodicals conceal the cover of the magazine so that in order to determine the issue enclosed it is necessary to raise the binder cover to see the magazine itself. This also has the disadvantages of covering up the illustrative material which is usually found on the front cover of most modern periodicals. The publishers go to great trouble and expense in providing attractive cover designs and very naturally anything which tends to minimize or destroy any benefit flowing therefrom is discouraged by them and the news sellers. One of the real advantages of the invention herein is that the periodical finds support in use and yet there is no concealing of the cover of the periodical or magazine when in normal position.

It is likewise true that in most binders it is difficult, if not impossible, to read freely to the edge of the printed material, which is most inconvenient. It is an object of the invention

herein to provide a periodical holder which permits a full vision of the reading material on any page without any inconvenience.

Most binders and magazine holders are not only unsuited but unadaptable to sizes of magazines other than that for which they were first intended. It is among the objects of the invention here to provide such a holder which, within reasonable limits, can be adjusted to fit and be useful with the several sizes of magazines without fuss or trouble.

In order to disclose the nature of the invention herein reference is made to the accompanying drawing, which illustrates only one of several forms which this invention may take. Like reference characteristics have been used to indicate like parts.

In the drawing:

Fig. 1 is a perspective view of my device with a periodical of exact size in position and shown in full lines, and with both larger and smaller periodicals shown in broken lines.

Fig. 2 is a fragmentary perspective view to more clearly illustrate the nature of the assembly of the device.

Fig. 3 is a sectional view on an enlarged scale taken on the line 3—3 of Fig. 2 and looking in the direction of the arrows.

Fig. 4 is a modification of the view shown in Fig. 3.

Fig. 5 is a sectional view showing a modified form of the backing or support member.

Fig. 6 is a perspective view of a rod on an enlarged scale.

As the drawing more particularly shows, the backing or support member 10 represents a sheet of lightweight, flexible, resistant material, preferably of fibreboard, which will stand a great deal of abuse, or a lightweight metal, such as aluminum alloys, which are likewise extremely resistant. Along one edge of the backing member 10 there is provided a folded or U shaped member 11, which is of some stiff resistant material and can be made of a lighter weight fibreboard or the like. The folded or U shaped member 11 is attached to the backing member 10 in any suitable manner so that it can be held in place and stand the wear to which the device is subject. One way of attaching the binding member 11 is by means of staples 12. The U shaped member is attached along the margin of the backing member 10 in such a manner that the inner portion of the fold or the bottom of the U does not engage the marginal edge to which it is secured, but provides a sufficient space to form a tube-like passage 14 along the margin. Since the portion of the tube-like passage 14 is to retain the rods 15 the U shaped member may be only long enough to provide such support and hence may be in more than one piece. The device also

includes two rods 15 which are adapted to be retained in the tubular space 14 in free engagement. At the outer end of each of these rods 15 there is formed a loop 16 or other stop member, which is preferably bent or shaped at right angles to the axis of the rods. Between the two stop members 16 is a resilient member 17 which can be a light spring elastic or of any other suitable form positioned by less resilient retaining means 18, which are retained against stops 16 in any suitable manner such as the knot 19. In Fig. 2 the spring 17, which is the resilient member, is shown held between two pieces of cord 18, having knots 19 acting against the urge of the spring member against the stop 16. Obviously, only one piece of cord 18 or non-resilient means may be used or the entire distance along the margin may be spanned by elastic or other resilient means and so accomplish the result and concept of the combination, but the preferable construction so far as now known is shown in Fig. 2.

It may very well be that the device shown in Fig. 3 will not present an attractive appearance because of the stapling or other holding means 12 and to overcome any unsightliness it may be desirable to cover the U shaped member 11 by a suitable covering 20, which may be retained in any of the well-known manners, such as lacing, stapling, gluing, etc. This form is shown in section in Fig. 4.

In Fig. 5 there is likewise shown a variant form of the backing member 10, which if made of a suitable material for the purpose, can have one of its marginal edges bent back on itself as at 21 to form the tube-like passage 14a, which passage may lie in a plane—viewed-in section as at Fig. 5—parallel to the backing member 10 or lying in the same plane as the backing member 10.

Referring now to Fig. 1, which shows the magazine or periodical 22 of the same size as backing 10 in place, the operating of the device is substantially as follows. The periodical is opened up preferably in the middle page where the stapling holding the pages together are placed. The lefthand group of pages is then inserted between the retaining member which comprises the resilient means 17 and the less resilient means 18 in the preferred form illustrated and the backing or U shaped member 11 and then folded back on itself to the normal position shown so that the entire magazine rests upon the backing member 10. This makes the magazine and the backing member 10 a unitary structure, but firm enough so that the pages will not fall on each other and stiff enough so that they will be held in upright position and there is no necessity for folding the pages of the magazine back on themselves into half pages in order to supply the rigidity necessary to make the magazine hold firmly enough to read comfortably.

Obviously, if the magazine is the same size such as 22 or smaller than the device of this invention, such as 23, the operation will be successful, but the present invention also is capable of being extended beyond the precise size of the backing member 10 and still provide satisfactory operation. In fact, the usefulness of the present holder may be extended to the limits described by the length of the pins 15 so long as they have adequate support within the tubular portion 14. The magazine 24 shown in Fig. 1 in broken lines is larger than the backing member 10 and still

the entire usefulness thereof is maintained. The magazine 24 is held in position on the backing by the urge of the resilient member 17.

When the magazine 22 is in position as illustrated in Fig. 1 the resilient member 17 and the less resilient members 18 if used, will occupy or assume the position of Fig. 1. However, since the resilient member 17 (and the less resilient member or members 18) act as the axis of a cylinder so that each page as it is read can be turned to lie against the back of the board 10 and parallel to its original position but on the opposite side of board 10. In this event the member 17 (and member 18) will assume the position illustrated in Fig. 2, due to the free rotation of rods 15 in the tubular space 14. By folding the pages back as indicated herein the magazine or periodical can be held readily and comfortably in one hand without any bending or folding of the reading matter and with all of the printing on each page, front and back, in full view.

It is further contemplated that all parts hereof may be strengthened and/or beautified by coatings and treatments of various kinds and this is included within the scope of the invention.

I claim:

1. A periodical holder comprising in combination a backing member provided with a tubular member along one margin thereof, rods with stops thereon held in free engagement in said tubular member for a portion of the distance and at opposite ends thereof including extension beyond the outer ends of said tubular member and resilient holding means retained between said stops.
2. A periodical holder comprising in combination a backing member provided with a tube-like member along a portion of one margin thereof, a pair of rods with stops thereon held in free engagement in said tube-like member at opposite sides of said backing member including extension beyond the length of said tube-like member, and resilient holding means retained between said stops.
3. A magazine holder comprising in combination, a backing member, a U shaped member attached along one margin of said backing member in such a manner as to form a tube, a pair of rods with stops thereon held in free but firm engagement at opposite ends of said tube, and resilient holding means under tension retained between said stops.
4. A magazine holder comprising in combination, a backing member, a U shaped member attached along one margin of said backing member in such a manner as to form a tube, a covering member for said U shaped member, a pair of rods with stops thereon retained in free but firm engagement at opposite ends of said tube, and resilient holding means under tension retained between said stops, said holding means including a resilient portion and one or more less resilient portions.

5. A periodical holder comprising in combination, a backing member, one margin of said member fashioned to form a tube-like structure, rods with stops thereon held in free engagement within said tube-like structure and at opposite ends thereof including extension beyond the length of said tube-like structure and resilient holding means retained between said stops.
